UNITED STATES PATENT OFFICE.

IGNACE L. BOSCH, OF HUNTINGTON, WEST VIRGINIA.

ARTIFICIAL HAND AND HARNESS THEREFOR.

1,318,260.

Specification of Letters Patent.

Patented Oct. 7, 1919.

Application filed January 22, 1919. Serial No. 272,504.

To all whom it may concern:

Be it known that I, IGNACE L. BOSCH, a citizen of the United States, residing at Huntington, in the county of Cabell and State of West Virginia, have invented new and useful Improvements in Artificial Hands and Harness Therefor, of which the following is a specification.

My present invention pertains to artificial hands and harnesses therefor; and it has for one of its objects to provide an artificial hand embodying a friction-creating protuberance through the medium of which the wearer of the hand is enabled to draw articles of various kinds toward himself.

Another object is the provision of an artificial hand embodying a carrying hook so constructed and arranged that it may be readily folded against the side of the artificial hand when it is desired to insert the hand in a pocket or the like.

Another object of the invention is the provision of improved and highly advantageous harness for attaching the hand to the body of the wearer and for enabling the wearer to manipulate the hand with great facility.

Other objects and practical advantages will be fully understood from the following description and claims when the same are read in conjunction with the drawings accompanying and forming part of this specification, in which:

Figure 1 is a view showing in proper relation my novel hand and harness.

Fig. 2 is a side elevation of the hand.

Fig. 3 is an inverted plan view of the same.

Fig. 4 is a detail section illustrative of the friction-creating protuberance on the lower jaw of the hand.

Fig. 5 is a plan view of said jaw illustrating the groove therein for the secure holding of a pencil, pen or the like.

Similar numerals of reference designate corresponding parts in all of the views of the drawings.

The lower jaw 1 of my novel artificial hand is carried by a shank 2 which is provided at 3 with a bifurcated standard in which is pivoted at 4 the upper jaw 5 of the hand. Suitably fixed in and depending from the forward portion of the jaw 1 is a pad or protuberance 6, of rubber or other friction-creating material. By virtue of this provision it will be manifest that the wearer of the hand is enabled by pressing the protuberance 6 downwardly upon sheets of

paper or the like to frictionally engage the said protuberance 6 with the sheets of paper so that the sheets may be conveniently drawn toward or pushed from the wearer. In the 60 preferred embodiment of the invention, the protuberance 6 and the complementary bore are of even diameter throughout as shown in Fig. 4, and hence the protuberance may be readily placed in and removed from the 65 socket, though there is little liability of the protuberance being casually displaced when the hand is in use. At the upper side of its forward portion the jaw 1 is serrated, as indicated by 7, and is provided with a groove 70 8 disposed and tapered as shown with a view to enabling the jaw 1 to securely hold a pencil in position for convenient manipulation through the medium of the artificial hand. The forward portion of the jaw 5 is 75 adapted to coöperate with the forward portion of the jaw 1 in the holding of a pencil and other articles, and the portions of the jaws in rear of the forward portion are preferably, though not necessarily, shaped as 80 best shown in Figs. 1 and 2. The jaw 5 is in the form of a lever, and its rear arm 9 is suitably connected with a controlling cable 10, said cable being by preference partly of chain and partly of strap, the strap indicated 85 by 11 being by preference connected through the medium of a snap hook 12 with the rear end of the chain. It will also be readily understood by comparison of Figs. 1, 2 and 3 that the jaw 1 is equipped with a hook 13 90 for the convenient carrying of buckets and other receptacles. The said hook 13 is hinged at 14 to the side of the jaw 1, and from this it follows that when it is desired to insert the artificial hand into a pocket, or is 95 otherwise desired to use the hand without entailing employment of the hook 13, the said hook 13 may be swung upwardly against and parallel to the standard 3 as shown in full lines in Fig. 2 and by dotted lines in Fig. 100 3. The hook 13 is shown in its working position in Fig. 1, and it will be observed that the said hook may be easily engaged with and disengaged from the bail of a bucket or the like.

At its rear end the shank 2 of the lower jaw 1 is suitably fixed to the forward end of a socket member 15 designed to receive the arm stump of the wearer, and at 16 is a sleeve member designed to be strapped around the upper portion of the arm of the wearer. This sleeve member 16 is provided

with opposite arms 17 which are hinged at 18 to arms 19 or the socket member 15 to provide for the necessary flexing of my improvement. At 20 and coincident with the 5 point of flexure is mounted a sheave 21 around which passes the strap portion 11 of the cable 10. It will be noticed here that the socket member 15 and the sleeve member 16 are strongly connected together, 10 notwithstanding the provision made for flexing, and by reference to Fig. 1 it will be noticed that the sleeve 16 is connected to the ends of a strap yoke 22 which is designed to straddle the adjacent shoulder of 15 the wearer. Manifestly when a heavy article such as a bucket of water or a suitcase is carried on the hook 13 of the artificial hand, the yoke 22 will serve to impose the 20 said weight on the shoulder of the wearer and will preclude the possibility of the socket member 15 and the sleeve member 16 moving downwardly in the sleeve of the wearer. Again it will be observed that the yoke 22 suspends and carries the sleeve 16, 25 the socket member 15 and the artificial hand carried by the latter.

At 23 is a yoke which is designed to receive the opposite shoulder of the wearer, and at 24 is a strap which effects permanent 30 connection of the yokes 22 and 23. The said strap 24 extends across at the back of the base of the neck which is advantageous inasmuch as it leaves the front portion of the body of the wearer entirely free from pressure. 35

The strap portion 11 of the controlling cable 10 is designed to be passed over the first-named shoulder of the wearer and to be carried from said point across the back 40 of the wearer to the point 25 indicated by dotted lines in Fig. 1, where it is permanently attached to the holding portion of the harness. The said point 25 is located ad-

jacent to the shoulder loop 23. At 26, Fig. 3, is the usual spring for yieldingly holding 45 the jaws 1 and 5 together.

By reference to Fig. 1 it will be understood that the strap 11 is carried around the first-named shoulder of the wearer. From this it follows that when the said 50 strap is positioned as illustrated in Fig. 1, forward movement of the artificial hand by the wearer will be attained by opening of the jaws 1 and 5, while when the wearer relaxes the said shoulder and permits the 55 strap 11 to ride up on the shoulder, the artificial hand may be extended without opening of the jaws. I would also have it understood that by manipulating the shoulder mentioned the wearer may through the 60 medium of the strap 11 nicely control the jaws 1 and 5. Again I would have it understood that by reason of the connection of the yoke 23 with the strap 11, the wearer, 65 by manipulating his left shoulder, is enabled to nicely control the jaws 1 and 5 without entailing any movement whatever of the right shoulder.

Having described my invention, what I claim and desire to secure by Letters-Pat- 70 ent, is:

1. An artificial hand comprising jaws, means for yieldingly holding the jaws together, and a lateral hook hinged to one of the jaws and adapted when not in use to 75 be folded parallel to the remainder of the hand.

2. In an artificial hand, the combination of jaws one of which has a bore at an angle to its outer side, a pad disposed in said bore 80 and projecting laterally from the outer side of the jaw; said pad being of friction-creating material, and means for yieldingly holding the jaws together.

In testimony whereof I affix my signature. 85
IGNACE L. BOSCH.
